UNITED STATES PATENT OFFICE.

FREDERICK WILLSON, OF READING, PENNSYLVANIA, ASSIGNOR TO T. A. WILLSON & CO., INC., OF READING, PENNSYLVANIA, A CORPORATION OF PENNSYLVANIA.

GOOGLES.

1,323,431.

Specification of Letters Patent.

Patented Dec. 2, 1919.

Application filed January 28, 1918. Serial No. 214,112.

To all whom it may concern:

Be it known that I, FREDERICK WILLSON, a citizen of the United States, residing at Reading, in the county of Berks and State 5 of Pennsylvania, have invented certain new and useful Improvements in Goggles, of which the following is a specification.

My invention relates particularly to spectacles or goggles having folding eye-guards, 10 and it consists mainly in improved lens-clamping means and guard connections as fully described by reference to the accompanying drawings, and the novel features of which are pointed out in the claims.

Figure 1 is an edge view of a pair of goggles embodying my improvements; one of the lens framings and its attached guard being shown in section on the line I—I of Fig. 3, with the guard in folded position 20 and the clamping device removed from the end-pieces; and the other being a full edge view with the parts in position for service.

Fig. 2 is a separate view of the clamping device and its pivoted carrier bar; the head 25 band being shown in engagement with the free end of the latter, and also with the side guard, as illustrated in Fig. 1.

Fig. 3 is a partial outer-face view of one of the lens framings, showing the engaged 30 clip band and one of the end-pieces in section.

Each lens framing, as shown, comprises a split lens-edge engaging frame 5 having a pair of projecting end pieces 6—6, which 35 are brought together to clamp the lens and spreadable to release the same. This lens frame 5 is formed with an inwardly turned marginal flange 8 arranged in lens-reinforcing contact with the rear face of the lens as 40 set forth in my Patent No. 1161100 issued November 23, 1915, so as to safely retain a fractured lens; said flange serving also in the present structure for conveniently securing thereto, by so-called pin-welding or 45 otherwise, the separately formed flange guard ring 10; to which latter an ordinary flexible side guard 11 is rigidly secured so as to permit of folding it toward the inner face of the lens as indicated in Fig. 1. The 50 head band 12 for securing the completed goggles is attached to the free end of each guard, by means of a rigid end bar 13 on the band, which bar is engaged with an in-

tegral strip 14 of the guard formed by parallel slits in the latter in well known manner.

My improved lens-clamping means and guard connection comprises a locking-clip band 16 formed of a sheet metal strip bent to encircle and clamp together the abutted 60 end-pieces 6—6 of the lens framing; the free ends of the spring band thus formed being normally in parallel relation and provided with apertures to form a pivoting jaw 17 in which one end 18 of a carrier bar 19 is pivotally engaged; and the portion of said band engaging the end-pieces having an inwardly projecting tit 20 adapted to engage a recess or aperture in an end-piece 65 as indicated in Fig. 3 so as to normally retain the band in its clamping position.

The pivoted carrier bar 19 is movable with the folding side guard 11 as indicated, and is connected to the latter at its opposite end 25; this connection, as shown, being effected through the medium of the head band 12, which is directly attached to the guard as previously described, by stringing said band through the transverse slot formed in said end 25 of the bar.

My invention thus provides that when the clip band 16 is detached from the end piece 6 it will be carried by its pivotally connected carrier bar 19, which bar is itself connected to the guard 11 by means of the band 12 attached to the latter; so that each clip band 16 may be readily removed from the end pieces, when it is desired to release the lens, yet remain attached to the corresponding guard 11; while when the clip band is normally attached to the end pieces, said carrier bar 19 freely turns in the pivoting jaw 17 of the clip band and permits it to fold down with the guard 11, and also gives support to the latter when both are thrown out to operative position; the tension upon the head band 12 being carried jointly by the guard 11 and the carrier bar connection to the attached clip band. The specific construction set forth may be modified within the invention as defined in the claims.

What I claim is:—

1. In an eye protector, the combination with a lens-edge framing provided with a pair of extending end-piece members having 105 a tit-engaging recess, of a detachably en-

gaged spring-clip band on the abutted end-piece members formed with a locking tip and a pivoting jaw.

2. In an eye protector, the combination with a lens-edge framing provided with a pair of extending end-piece members, and with a side guard foldably attached to said framing; of a detachable locking-clip band for the abutted end-piece members formed 10 with a pivoting jaw, and a carrier bar for said clip band connected at one end to said jaw and at its other end to the foldable side guard.

3. In an eye protector, the combination 15 with a lens-edge framing provided with a pair of extending end-piece members, and with a side guard foldably attached to said framing; of a detachable locking-clip band for the abutted end-piece members formed 20 with a pivoting jaw, a carrier bar for said clip band connected at one end to said jaw, and a head band connected to the outer

portions of said foldable guard and carrier bar.

4. In an eye protector, the combination 25 with a lens-edge framing provided with a pair of extending end-piece members, and with a side guard foldably attached to said framing; of a detachable locking-clip band for the abutted end-piece members formed 30 with a pivoting jaw, a head band attached to the outer portion of said side guard, and a carrier bar pivotably connected to said clip band and having a transversely slotted end engaged by said head band. 35

5. In an eye protector, the combination with a lens-edge framing provided with a pair of extending end-piece members, of a detachable frictionally engaged spring-clip band on said members formed of bent-up metal having abutting portions arranged 40 to form a pivoting ear.

In testimony whereof I affix my signature.
FREDERICK WILLSON.
